UNITED STATES PATENT OFFICE.

FREDERICK WILLIAM BOULTON, OF BOOTLE, NEAR LIVERPOOL, ENGLAND.

LIFE BOAT OR RAFT.

1,202,961.

Specification of Letters Patent.

Patented Oct. 31, 1916.

Application filed February 2, 1915, Serial No. 5,678. Renewed August 24, 1916. Serial No. 116,703.

To all whom it may concern:

Be it known that I, FREDERICK WILLIAM BOULTON, a subject of the King of Great Britain, residing at Bootle, near Liverpool, England, have invented a certain new and useful Improved Life Boat or Raft, of which the following is a specification.

The principal object of the present invention is to provide a reversible life boat or raft of a simple, compact, efficient and comparatively inexpensive nature, so constructed that when thrown into the water, and irrespective of its position the same may be readily opened up to provide extended sides equipped with seats whereby the draft of the life boat or raft is effectively increased and the seating capacity thereof greatly enlarged.

A further object is to provide a life boat or raft of the above type which may be compactly stored upon deck flatwise or upon edge.

Other and further objects of the present invention reside in the providing of general details of construction and arrangement and combination of parts as will hereinafter more fully appear.

The invention consists of the improvements hereinafter described and finally claimed.

The nature, characteristic features and scope of the invention will be more fully understood from the following description, taken in connection with the accompanying drawings forming part hereof and in which:

Figure 1, is a longitudinal sectional view of the life boat or raft, Fig. 2, is a plan view thereof, and Fig. 3, is a view in transverse section of the same.

The life boat or raft of the present invention is built up of an inner framework formed of longitudinal side members 1, and cross members 2, and an outer framework forming longitudinal members 3, and cross end members 4. The outer members 3, may be, as shown in Fig. 3, of lattice work, this open form being preferred for the sake of lightness, as is usual with raft constructions, although the sides may be built solid.

The end spaces between the members 2, and 4, are preferably arranged to carry buoyancy tanks such as 5, or in these spaces bread and water receptacles may be arranged with openings both top and bottom so that access thereto may be had from either face of the boat or raft. The buoyancy tanks

may also be provided between the inner longitudinal members 1, and the outer members 3. The ends 6, of the raft may be planked over either solid or open framework as desired. A central partition 7, is preferably arranged horizontally of the inner part of the raft to form a floor and is made water-tight with the inner framework 1, and 2. Collapsible side members 8, hinged to the inner part of framework 8', and similar members 9, hinged to the outer part of framework 8', are provided on each side and upon each face of the raft, cross-seats 10, being hinged between these two members 8, and 9. Hinged end pieces 13, are provided, with which the members 9, may be interlocked in any suitable manner. Each inner member 8, is preferably in a single piece and of such width that it will meet the opposite member along the center line of the raft. It may if desired be made water-tight by means of packing along the edge, although this is not essential in view of the center partition 7. Any desired means may be arranged to lock these parts in the closed position. With a boat or raft floating in the water, both faces of course being collapsed, the top can be opened up and the bottom formed of the extendible inner members will form the bottom of the central chamber of the raft, closing this in completely water-tight manner. The inner edges, therefore, of these inner extendible members are preferably lined with rubber or like packing material at such parts as form joints when in the folded position. As shown in the drawings, central posts 14, can be arranged slotted to receive wedge members 15, carried by the extendible sides, but, of course, it is obvious that the fastening can take place in other ways. The inner chamber can be provided with a number of cross-members or struts forming seats 16, and also forming cross bracing stays for the raft. The framework of the boat can be strengthened by angle bars not shown at any places where this is found desirable. The outer extendible sides may be locked in position, for instance by eyes 18, on the end pieces 13, passing through holes in flanges 19, carried by the ends of the outer extendible members, through which eyes locking pins can pass. Other suitable forms of locking means can, of course, be devised. These extendible members according to the present invention when in the folded posi-

tion are adapted to lie substantially in the same plane as the outer faces of the raft, so that the raft may be smoothly passed over the deck of a vessel.

5 It is preferred to arrange a peculiar mounting of the seats on the inner and outer extendible members. Brackets 20, are arranged on opposite sides of these members, pivotal pins 21, being carried by these brackets, so that the pins on the inner edges form pivots in an axis lying underneath the seat, while the pivotal pins on the brackets on the outer extendible members lie in an axis above the seats. The seat members may 10 be provided at their sides with metal strips 22, bent up at one end and down at the other in somewhat elongated S-shape.

Air tubes not shown can be arranged between the outer and inner frameworks to 20 increase the buoyancy of the raft. Also the raft can be provided along its longitudinal sides with life lines and at each end with tow ropes, or the like devices.

It will be seen that the raft of the present 25 invention has the advantage that it can be thrown into the water in any position, and whichever face is floating upward that face can be opened up to provide extendible seat members for increasing the effective draft 30 of the raft and seating capacity of the same, while the arrangements providing for the extra seating form a water-tight bottom for the raft on the other face. The extra seats will, of course, be at a higher level than the 35 usual seats of the boat. Those, arranged in the central chamber, are provided preferably with spaces or lockers to carry the oars or paddles, lights and the like. By the present raft construction a raft having extendible sides is provided without the necessity 40 of canvas sides or like pieces. The extendible sides can, of course, be provided with rowlocks and the usual gear such as masts can be stored in such desirable places as under the fixed seats in the central chamber of 45 the raft, all these parts being such that they can be attainable from either side of the raft. This raft can be stored flat upon the deck one upon another in pairs, or of course, 50 can be stored also on the edge. It is obvious that the ends of the boat can be hollow to receive tanks of oil for the purpose of calming the waves.

What I claim is:

55 1. A reversible life boat or raft embracing a spaced inner and outer frame to provide a central passenger receiving chamber, top and bottom decks covering the spaces between adjacent frames and extendible side 60 pieces hinged to the respective decks of the boat.

2. A reversible life boat or raft embracing a spaced inner and outer frame to provide a central passenger receiving chamber, top 65 and bottom decks covering the spaces be-

tween adjacent frames, extendible spaced side pieces hinged to the respective decks of the boat and collapsible seats operatively disposed between adjacent side pieces.

3. A reversible life boat or raft embracing a spaced inner and outer frame to provide a central passenger receiving chamber and surrounding buoyancy chambers, top and bottom decks covering the buoyancy chambers, extendible spaced side pieces hinged to the respective decks of which the inner edges of the inner side pieces meet at the boat center in collapsed position and collapsible seats operatively disposed between adjacent side pieces. 70 75

4. A reversible life boat or raft embracing a spaced inner and outer frame to provide a central passenger receiving chamber and surrounding buoyancy chambers, top and bottom decks for covering the buoyancy chambers, extendible spaced side pieces hinged to the respective decks of which the inner edges of the inner side pieces meet at the boat center in collapsed position, means 80 85 for locking the extendible side pieces in extended and collapsed positions and collapsible seats between adjacent side pieces.

5. A reversible life boat or raft embracing a spaced inner and outer frame to provide a central passenger compartment and surrounding buoyancy chambers, top and bottom decks for the said chambers, and collapsible members hinged to the respective decks operative for closing or permitting access to the passenger compartment independent of the position of immersion of the boat. 90 95

6. A reversible life boat or raft embracing a spaced inner and outer frame to provide a central passenger receiving chamber, top and bottom decks covering the spaces between adjacent frames and collapsible members operatively connected with respect to the respective decks of the boat or raft for extending the frame work to increase the draft of the boat or raft. 100 105

7. A reversible life boat or raft embracing a spaced inner and outer frame to provide a central passenger receiving compartment, top and bottom decks covering adjacent frames, collapsible side and end members 110 115 operatively connected with respect to the respective decks of the boat or raft for vertically extending the frame work of the boat or raft and collapsible seats operatively connected between adjacent side members. 120

8. A reversible life boat or raft embracing a spaced inner and outer frame to provide a central passenger receiving compartment, which compartment is divided by a substantially central flooring and collapsible members operatively connected to the respective faces of said boat or raft for normally closing said passenger compartment and which collapsible members are operative for vertically extending the said frames. 125 130

9. A reversible life boat or raft embracing a spaced inner and outer frame to provide a central passenger receiving compartment which compartment is divided by a substantially central flooring, collapsible side and end members operatively connected with respect to the respective faces of said boat or raft for vertically extending said frame work and collapsible seats operatively connected between adjacent side members.

10. A reversible life boat or raft embracing a buoyancy frame work forming top and

bottom central passenger compartments including complemental decks surrounding each compartment and collapsible side and end members operatively connected with the respective decks of the boat or raft for vertically extending said frame work.

In testimony whereof, I have hereunto signed my name.

FREDERICK WILLIAM BOULTON.
